UNITED STATES PATENT OFFICE.

RICHARD A. POHLMANN, OF JEFFERSON CITY, MISSOURI.

DESIGN FOR A WATCH-CHARM.

40,694.

Specification for Design.

Patented May 17, 1910.

Application filed March 10, 1909. Serial No. 482,623. Term of patent 7 years.

To all whom it may concern:

Be it known that I, RICHARD A. POHLMANN, a citizen of the United States, residing at Jefferson City, in the county of Cole and State of Missouri, have invented a new, original, and ornamental Design for Watch-Charms, of which the following is a specification, reference being had to the accompanying drawing, forming part thereof.

The figure is an elevation of the design.

The design consists of the representation of a baseball having a suspending eye at one edge, crossed bats at the base or juncture of

the eye with the body, masks in opposite angles formed between the ends of the bats, figures of baseball players at opposite sides of the eye and in the angles formed between said eye and body, and the representation of a baseball team upon the center of the body.

I claim;

The ornamental design for a watch charm, substantially as shown and described.

RICHARD A. POHLMANN.
